CLAIM

The ornamental design for a vehicle cargo organizer, as shown and described.

DESCRIPTION

FIG. 1 is a top, front, right side perspective view of an open vehicle cargo organizer of the present invention; FIG. 2 is a left side elevational view of the vehicle cargo organizer of FIG. 1 shown in closed position; FIG. 3 is a front elevational view of the vehicle cargo organizer of FIG. 1 shown in closed position; FIG. 4 is a back elevational view of the vehicle cargo organizer of FIG. 1 shown in closed position; FIG. 5 is a top plan view of the vehicle cargo organizer of FIG. 1 shown in closed position; and, FIG. 6 is a bottom plan view of the vehicle cargo organizer of FIG. 1 shown in closed position. The right side elevational view is a mirror image of the left side as shown in FIG. 2.
